CLAIM

The ornamental design for a set of top and bottom edge recesses of a portable power device as shown and described.

DESCRIPTION

FIG. 1 is a front perspective view of a set of top and bottom edge recesses of a portable power device of our new design;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

The dot-dot broken lines in the drawing illustrate portions of the set of top and bottom edge recesses of a portable power device that form no part of the claim.

1 Claim, 7 Drawing Sheets
